UNITED STATES PATENT OFFICE.

WILLIAM L. HORNKE, OF EVANSTON, ILLINOIS.

CUTLERY SHARPENER.

Application filed September 7, 1920. Serial No. 408,560.

To all whom it may concern:

Be it known that I, WILLIAM L. HORNKE, a citizen of the United States, residing at Evanston, in the county of Cook and State 5 of Illinois, have invented certain new and useful Improvements in Cutlery Sharpeners, of which the following is a specification.

This invention relates to improvements in cutlery sharpeners.

10 As distinguished from that type of sharpeners in which grinding instrumentalities are employed for effecting the sharpening of the tool, the present invention contemplates a device in which the sharpening is accomplished by the removal of a thin sliver or slivers therefrom, dependent upon the angular disposition of the cutters with respect to each other, whereby to obtain a fine 15 sharpened edge free from irregularities and burrs and thinned or attenuated proportionately to the thickness of the stock of the tool. Regardless, therefore, of the character of the tool, the edge desired to be imparted thereto readily may be determined and controlled.

A further object of the invention is the provision of a device of the character mentioned which is of a portable character, thus adapting it to be carried about with facility 30 and ease, and one which includes means for its ready attachment to a table top, bench or similar location when necessity for its use arises.

The invention also aims to provide a 35 sharpener for the purposes stated, the construction of which is such that the sharpening of the tool may be effected with the expenditure of but minimum effort and without the exercise of special skill, and in which 40 construction are embodied simple and efficient means for adjusting the cutters and holding them in adjusted position to adapt the device to the particular tool to be operated upon.

45 Other objects and advantages will appear as the nature of the improvements is better understood, the invention consisting substantially in the novel construction, combination and arrangement of parts hereinafter 50 fully described, illustrated in the accompanying drawings, and finally pointed out in the appended claims.

The form of the invention herein disclosed is considered as a desirable embodiment thereof, but this disclosure is to be considered from an illustrative standpoint and,

therefore, is not to be taken in a restrictive or limiting sense.

In the drawings—

Fig. 1 is a side elevation of a cutlery 60 sharpener constructed in accordance with the present invention, and illustrated as applied to a table top;

Fig. 2 is a front elevation thereof;

Fig. 3 is a top plan view;

Fig. 4 is a transverse sectional view 65 through the upper portion of the sharpener, illustrating the manner in which the cutters are held in relative position;

Fig. 5 is a similar view with a modified 70 form of the sharpening instrumentalities;

Referring in detail to the accompanying drawings, the numeral 10 designates a U-shaped supporting bracket at the lower end of which is arranged a perforated toe 11, 75 which extends at right angles to the shank of said bracket, said toe being screw-threaded for receiving a fastening screw 12 having a winged head 13 for its convenient rotation. The inner end of said screw 12 has 80 a clamping button 14 swivelled thereto, said button being designed to take against one surface of the support 15 to which the sharpener is applied. This support may be

85 a table top, bench or other object and co-operating with said fastening screw is a head 16 arranged at the upper end of the shank of the bracket, the inner face of which lies parallel with the toe 11 and is provided with a plurality of ribs 17 to afford tight 90 engagement of the bracket with the support to which it is applied when the fastening screw 12 is properly adjusted. Associated with the head 16, and merging into the same, 95 is an inclined cutter rest 18. This rest is in the form of an arm, the upper extremity of which is reduced to provide a neck 19, and said rest 18 affords a support for a plurality of cutters 20. The cutters 20 are 100 segmentally curved, the same being formed of highly tempered steel to provide the requisite cutting action, and their contiguous faces are beveled to provide knife edges 21 against which the tool to be sharpened is drawn. One end of each of the 105 cutters 20 is more sharply curved than the other end thereof, and in the associated application of the cutters to the rest 18 the correspondingly curved ends are arranged 110 uppermost, in accordance with the thickness of the edge which it is proposed to impart to the tool to be sharpened, these correspond-

2
ingly curved ends thus projecting upwardly beyond the extremity of the rest 18 for the presentation thereto of the tool.

For holding the cutters 20 in applied position to the rest 18 a clamping plate 22 is employed. This clamp is of substantial width so as to extend over the face of the rest 18, as clearly illustrated in Fig. 2, and its upper end is provided with a pair of spaced lugs 23 which embrace the sides of the neck 19. By the formation of the spaced lugs 23 the upper end of the clamping plate 22 is notched for receiving the cutters 20. The cutters 20 are arranged in the space between the lugs 23, and fit between the neck 19 and the clamp 22, and in this position they are held in the required angular relation to each other as may be required for the shape and thickness of the edge which it is desired to impart to the tool.

The clamp 22 has a perforation intermediate its ends for receiving an anchoring bolt 24, which bolt has a squared neck 25 seated in a corresponding socket in the rest 18, the head of the bolt fitting snugly against the rest 18. The threaded end of the bolt 24 has a winged nut 26 applied thereto, and surrounding the shank of the bolt 24 is a coil spring 27 which is received by a socket 28 formed in the clamp 22 and surrounding the perforation thereof through which the bolt 24 passes. The spring 27 affords resilient mounting for the clamp 22 and permits the clamp to yield with respect to the rest 18 when the cutters 20 are inserted therebetween. The spring 27, by reason of this yielding mounting of the clamp 22, enables the clamp to hold the cutters 20 in place during adjustment of the thumb nut 26 for permitting rearrangement of the cutters when it is required to change their angular relation.

Mounted in the rest 18 is a fulcrum screw 29 the free end of which is rounded and is received by a depression 30 formed in the lower end of the clamp 22. The latter, therefore, finds a support on the screw 29, and by the adjustment of the latter the distance at which the clamp 22 is spaced from the rest 18 may be regulated.

By reference to Fig. 4 it will be seen that both the inner and outer ends of the cutters 20, when applied to the rest 18, extend in divergent relation, and in seating the cutters upon said rest the lower or inner ends thereof are caused to contact with the anchoring bolt 24. A set screw 31 is arranged in one of the lugs 23, its inner end impinging against one of the cutters 20, and when said set screw 31 is tightened pressure is exerted in a direction laterally of the cutters 20 to hold them in proper relation between the lugs 23.

As illustrated in Figs. 1 to 4, inclusive,

the cutters 20 will act upon opposite sides of the tool to be sharpened. However, where it is desired to operate upon only one side thereof the construction illustrated in Fig. 5 is employed. In this construction 70 but one of the cutters 20 is utilized, a co-operating guide finger 32 being associated therewith. This finger is provided with no cutting edge. Its lower end is provided with a recess 33 designed to receive the anchoring bolt 24 and upon which bolt the finger 32 rests, and said finger is interposed between the set screw 31 and the cutter 20 so that the pressure exerted by said screw upon said finger will act to hold the latter 80 and the cutter 20 in applied position.

The upper end of the clamp 22, between the lugs 23 thereof, is formed into a concave depression 34 to facilitate movement 85 of the tool between the cutters as the tool is being sharpened.

In the use of the herein described sharpener the cutters 20 are assembled in the manner illustrated in Figs. 1 to 4, inclusive, the exposed ends thereof providing 90 a V-shaped notch into which the tool to be sharpened is introduced. This is illustrated by dotted lines, and when so introduced the tool is drawn through the space between the cutters. As the sides of the 95 tool are brought into contact with the knife edges 21 a sliver of the stock of the tool is removed from each side, and from end to end of the cutting edge of the tool. This action is repeated until the edge has been 100 reduced to the desired degree, whereupon it will be found that the cutting edge as imparted thereto is of the required sharpness without the presence of irregularities or burrs thereon. Obviously, the V-shaped 105 notch between the cutters imparts a tapered cross section to the cutting edge of the tool, and this may be relatively thin or relatively thick in accordance with the angular disposition of the cutters 20 with respect to each other. If but one cutter is employed, as in the construction illustrated in Fig. 5, the sliver is removed from but one side of the tool, the other side not being acted on.

The invention herein illustrated and described may be used for the sharpening of knives and other implements provided with cutting edges, and by reason of the inclination of the rest 18 the cutters 20 are placed in a convenient position for the application of the tool between the same and the drawing of the tool therethrough to effect its sharpening.

By referring to Fig. 4 it will be observed that by shifting the cutters 20 in respect 125 to each other, as designated by the dotted line position of one of the cutters, the V-shaped space between the exposed ends of the cutters may be increased, thus enabling 130 a greater taper to be imparted to the sharp-

ened edge of the tool. By reversing the position of the cutters, that is to say, by arranging the inner ends of the cutters, as shown in Fig. 4, so as to project at the exterior of the sharpener, the taper of the edge may be decreased, the curvature of the cutters 20 being somewhat irregular to provide for these conditions.

I claim:

10 1. A sharpener of the class described, comprising a support, a clamping plate fulcrumed at one of its ends on said support and having a notch at its other end, cutting means arranged in the notch of the clamp-

15 ing plate, and clamped by the latter to said support, and locking means for holding the plate and the cutting means in clamped relation to said support.

20 2. A sharpener of the class described, comprising a support, a clamping plate fulcrumed at one of its ends on said support and having a notch at its other end, cutting means arranged in the notch of the clamp- 25 ing plate and clamped by the latter to said support, locking means for holding the plate and the cutting means in clamped relation to said support, and a yieldable connection included in said locking means to permit the clamping plate to yield in relation to said 30 support.

3. A sharpener of the class described, comprising an inclined support, cutting means associated therewith, a clamp for holding said cutting means on said support, 35 and means for holding said cutting means in adjustable relation to said clamp.

4. A sharpener of the class described, comprising an inclined support, means associated with said inclined support to hold the same in applied position in use, cutting means associated with said inclined support, a clamp for holding said cutting means on said support, and means for holding said cutting means in adjustable relation to said 45 clamp.

5. A sharpener of the class described, comprising an attaching bracket including a perforated toe at one end thereof and a head at its other end, a fastening screw associated with said perforated toe and cooperating with said head to hold the bracket in applied position in use, a support carried by said bracket, cutting means associated with said support, a clamp associated 55 with said support for holding said cutting means thereon, and means associated with said clamp for permitting adjustment of said cutting means.

6. A sharpener of the class described, comprising a support, a clamping plate fulcrumed at one of its ends on said support and having a notch at its other end, cutting means arranged in the notch of the clamping plate and clamped by the latter to said support, locking means for holding the 65

plate and the cutting means in clamped relation to said support, and means carried by the plate and cooperating with the cutting means for adjustably mounting the cutting means in the notch of the plate. 70

7. A sharpener of the class described, comprising a support, cutting means associated therewith, a clamp associated with said support and provided with oppositely disposed lugs which embrace said cutting 75 means to hold the latter in position on said support, and means for locking said clamp in relation to said support for locking the cutting means thereon.

8. A sharpener of the class described, comprising a support, cutting means associated therewith, a clamp associated with said support and provided with oppositely disposed lugs which embrace said cutting 80 means for holding the latter on said support, an anchoring bolt carried by said support and passing through said clamp, and a locking device carried by said bolt and cooperating with said clamp to lock the cutting means in fixed relation to said support. 85

9. A sharpener of the class described, comprising a support, a clamp associated therewith, a fulcrum member carried by said support and with which said clamp 95 engages to space the latter from said support, cutting means arranged between the support and said clamp, and means cooperating with said clamp to lock the cutting means in fixed relation to said support. 100

10. A sharpener of the class described, comprising a support, a fulcrum member carried by said support, a clamp associated with said support and engaging said fulcrum member to be held in spaced relation 105 thereby with respect to said support, an anchoring bolt carried by said support and passing through said clamp, cutting means arranged between said clamp and said support, and a locking device carried by said anchoring bolt and cooperating with the clamp to lock the cutting means in fixed relation to said support. 110

11. A sharpener of the class described, comprising a support, a fulcrum member carried thereby, a clamp associated with said support and having one of its ends in contact with said fulcrum member, said clamp being provided with oppositely disposed lugs arranged in spaced relation, cutting means embraced by said lugs and arranged between said clamp and said support, and means cooperating with said clamp to lock said cutting means in fixed relation to said support. 115

12. A sharpener of the class described, comprising a support, an adjustable fulcrum member carried by said support, a clamp having one of its ends in contact with said fulcrum member, the other end 130

of said clamp being provided with oppositely disposed spaced lugs, cutting means arranged between said clamp and said support and embraced by said lugs; an anchoring bolt carried by said support and passing through said clamp, said clamp being provided with a socket adjacent to and surrounding said anchoring bolt, a spring surrounding said bolt and seated in said socket, and a locking device carried by said bolt and cooperating with said clamp to lock the cutting means in fixed relation to said support.

13. A sharpener of the class described, comprising a support, a clamping plate fulcrumed at one of its ends on said support and having a notch at its other end, a pair of reversely-arranged segmentally-curved cutters arranged in the notch of the clamping plate and clamped by the latter to said support, said cutters providing a V-shaped space therebetween for receiving the tool to be sharpened, the contiguous faces of said cutters being beveled to provide knife edges at corresponding portions of the cutter, and locking means for holding the plate

and the cutters in clamped relation to said support.

14. A sharpener of the class described, comprising a support, a clamp associated therewith, an anchoring bolt carried by said support and on which said clamp is mounted, said clamp being provided with oppositely disposed spaced lugs, a pair of reversely curved cutters arranged between said lugs and the clamp and said support, the contiguous faces of said cutters being beveled to provide knife edges at corresponding portions of the cutters, the exposed ends of the cutters being arranged in divergent relation and forming a V-shaped space for receiving the tool to be sharpened, and means carried by said anchoring bolt and cooperating with said clamp to lock the cutters in fixed relation to said support.

In testimony whereof I have hereunto signed my name in the presence of two subscribing witnesses.

WILLIAM L. HORNKE.
